UNITED STATES PATENT OFFICE.

JOHN W. SMITH, OF PHILADELPHIA, PENNSYLVANIA.

AIR-COOLING MECHANISM FOR INTERNAL-COMBUSTION ENGINES FOR FLIGHT-MOTORS.

1,341,444.

Specification of Letters Patent.

Patented May 25, 1920.

Application filed September 12, 1916. Serial No. 119,614.

To all whom it may concern:

Be it known that I, JOHN W. SMITH, of Philadelphia, in the county of Philadelphia and State of Pennsylvania, have invented 5 certain new and useful Improvements in Air-Cooling Mechanism for Internal-Combustion Engines for Flight-Motors, of which the following is a specification, reference being had to the accompanying drawings.

10 My invention relates to an air cooling system by means of which I deflect a sufficient quantity of the air current created by the motion of an aeroplane through compartments or channels formed for the purpose in such 15 a way as to effectually cool the interior of the cylinders, pistons, connecting rods, cranks and bearings of the engine. More particularly I provide in the region of the crank case of the engine an air collecting device 20 vice provided with openings so framed and arranged as to create very high air pressure, which by suitable connections is led to, and circulates in contact with the parts which have been named for the purpose of cooling 25 them.

I have found in practice that the proper circulation of air through a crank casing in such an engine is dependent upon the proper construction and positioning of openings 30 through which the air enters. Air circulation thus induced is of far more value than circulation which can be obtained from the fan. This is due to the very high speed at which modern aeroplanes fly, say from one 35 hundred to one hundred and fifty feet per second, which create greater air pressure than can be induced by a fan. By taking advantage of this velocity and the resulting air pressure and properly constructing and 40 positioning air openings arranged to induce circulation through the crank casing and surrounding parts, I secure a much more effective cooling of the heated parts than is accomplished by the use of the fan.

45 I supplement the air current thus induced by means of a fan contained within a fan housing. This is so constructed and housed that the air which has circulated around the parts of the mechanism for the purpose 50 of cooling them, and which has thereby taken up a considerable quantity of lubricating oil, is by the centrifugal effect of the fan caused to part with most of this oil, which is thereupon driven upon collecting webs and 55 thence collected and led back for reuse.

In the accompanying drawings, Figure I, is a vertical section through an internal combustion engine having air circulating means applied to it embodying my invention.

Fig. II, is a cross section along the line II, 60 II, of Fig. I.

Fig. III, is a view of the inner surface of the housing of the air fan, and

Fig. IV, is a view similar to Fig. I, of an engine having the parts reversed in relation 65 to the direction of the motion of the machine, but also having air circulating mechanism applied thereto embodying my invention.

Referring to Figs. I, and II, I will first, for the sake of clearness, briefly refer to those 70 parts of the machine which must be enumerated because they need to be cooled, but which in themselves do not constitute my present invention:

The engine is provided with a plurality 75 of cylinders which as shown are arranged radially in a common plane. Each cylinder 1, is provided with a piston 2, with a pivoted pitman 3, operating upon a crank 4, on the crank shaft 5. The pitmen and cranks are 80 all inclosed within a crank casing 6, which is in free communication with the lower end of the cylinder. To the rear of this crank casing is a somewhat smaller casing 7, containing the valve gear and to the rear of this is 85 a housing 8, containing a fan 9, set upon the main shaft.

In the embodiment of my invention which I have shown I provide in the casing structure an annular air chamber 10, surrounding 90 the valve gear casing between the fan housing and the crank casing. Around the periphery of this chamber are provided funnels 11, facing the front of the machine and so placed that their mouths are opposite the intervals between the radiating cylinders, so 95 that the motion of the machine creates very high air pressure in the air chamber.

After passing through the chamber 10, this air is discharged through apertures 12, 100 immediately alongside of the lower ends of the cylinders into the crank casing 6. After circulating therethrough this air passes by way of apertures 13, through the valve gear casing 7, and thence by way of apertures 14, 105 and 15, into the housing for the fan 9, through the open end of which it is ultimately discharged.

In this way a constant circulation of cooling air is maintained in contact with the 110

parts contained in the crank casing 6, including the interior of the cylinders.

The air chamber 10, includes the rear sides of the cylinders within itself. Trouble has 5 been experienced with previous constructions due to the unequal cooling of the front and rear of the cylinders. By my present invention I overcome this by conducting cooling air directly to the rear side of the cylinders, while their fronts are cooled directly by virtue of the motion of the machine.

The fan housing 8, has a curved periphery 20, with a recurved lip 21, surrounding its rear aperture. Within the curved periphery are set diagonal baffles 22. From the lower point of the curved periphery leads a pipe 23 which returns oil to an oil sump 24. The oil having been taken up by the air in the course of its circulation around the various lubricated parts, is thrown off therefrom by the centrifugal action of the fan 9, and after being caught by the baffles 22, and guided thence behind the lip 21, falls down and runs out by way of the pipe 23.

In Fig. IV, very much the same mechanism is shown with the direction of the parts reversed for application to mechanism where the machine advances in the opposite direction. Without recapitulating all the 25 parts, it will be plain from an inspection of the drawing that air received by the funnels 51, is discharged into a casing 50, whence it passes by apertures 52, into the crank casing, from whence it passes into the valve 35 casing, and thence by apertures 14, and 15, into the fan housing.

As I have shown in my invention, the funnels are directed toward the advance end of the machine and create pressure which 40 drives air through the crank casing. The same result may, however, be accomplished by funnels turned toward the rear of the machine inducing suction.

Having thus described my invention, I 45 claim:

1. An air cooling system for internal combustion flight motors comprising a crank casing, an air chamber in proximity thereto, openings around the periphery of said air chamber so arranged and positioned that the motion of the machine creates air pressure within said air chamber, and connections whereby this air is distributed to the crank casing for the purpose of cooling the parts 55 therein.

2. In an internal combustion engine for aeroplanes having a series of radially ar-

ranged engine cylinders the combination of a casing structure inclosing the engine connecting rods and cranks with the engine cylinders projecting radially therefrom, and a series of air intake funnels on said casing structure with their openings corresponding to the cylinder interspaces for forcing cooling air into said casing structure to the in- 60 closed engine parts.

3. In combination with an internal combustion engine having a series of radially placed cylinders surrounding a circular crank casing, air circulating means which 70 comprise an air chamber in a plane immediately to the rear of that which contains the radially placed cylinders; a series of funnels mounted around the periphery of this chamber with their openings corresponding to the interspaces between adjoining cylinders, and connections whereby the air received within the air chamber is led 75 into and passed through the crank casing.

4. In an internal combustion engine, the 80 combination of a series of radially placed cylinders surrounding a circular crank casing, and air circulating means for cooling said cylinders and adjacent parts, which comprise a circular air chamber situated to 85 the rear of the plane of the cylinders, and receiving within itself a portion of their rear sides, air funnels with flaring mouths surrounding this air chamber, and means whereby the air from this air chamber is led 90 to and through the crank casing.

5. In combination an internal combustion engine having a fan mounted upon its shaft; air propelling means; chambers and passages whereby said air is caused to pass over 95 mechanism of the engine requiring cooling prior to contact with the fan; a housing for said fan having a curved periphery; an overhanging lip around the edge of this periphery; inclined baffles mounted within the 100 periphery, and an outlet pipe at the bottom of the periphery whereby oil from the air passing through the fan driven by centrifugal force against the periphery of the housing, is collected and discharged through said 105 pipe.

In testimony whereof I have hereunto signed my name, at Philadelphia, Pennsylvania, this ninth day of September, 1916.

JOHN W. SMITH.
